UNITED STATES PATENT OFFICE

164,286

ELECTRIC CERAMIC KILN

Joseph J. Darby, Jr., Dallas, Tex.

Application August 19, 1949, Serial No. 4,608

Term of patent 3½ years

(Cl. D81—10)

To all whom it may concern:

Be it known that I, Joseph J. Darby, Jr., a citizen of the United States of America, residing at Dallas, county of Dallas, State of Texas, have invented a new, original, and ornamental Design for an Electric Ceramic Kiln, of which the following is a specification, reference being had to the accompanying drawings, forming a part hereof.

Figure 1 is a perspective view of an electric ceramic kiln showing my new design.

Figure 2 is a top plan view of the kiln.

Figure 3 is a rear elevational view of the kiln.

I claim:

The ornamental design for an electric ceramic kiln, as shown.

JOSEPH J. DARBY, JR.
